UNITED STATES PATENT OFFICE

109,733

DESIGN FOR A SEWING CASE OR SIMILAR ARTICLE

James H. Reichart, Muncie, Ind.

Application December 6, 1937, Serial No. 73,402

Term of patent 7 years

To all whom it may concern:

Be it known that I, James H. Reichart, a citizen of the United States and a resident of Muncie, county of Delaware, and State of Indiana, have invented a new, original, and ornamental Design for a Sewing Case or Similar Article, of which the following is a specification, reference being had to the accompanying drawing, forming part thereof.

In the drawing, Fig. 1 is a top plan view of the sewing case or similar article, and Fig. 2 is an elevational view thereof, showing my new design.

I claim:

The ornamental design for a sewing case or similar article, as shown.

JAMES H. REICHART.
